(57) **CLAIM**

I claim the ornamental design for a plasma gun, as shown and
described.

DESCRIPTION

FIG. 1 is a left side view of one embodiment of the plasma
gun;

FIG. 2 is a top side view of FIG. 1;

FIG. 3 shows a bottom side view of FIG. 1;

FIG. 4 shows a front side view of FIG. 1;

FIG. 5 shows a back side view of FIG. 1; and,

FIG. 6 shows a right side view of FIG. 1.

Any surfaces of the design not shown, including interior
surfaces and any surfaces shown in broken lines, form no part
of the claimed invention.

1 Claim, 6 Drawing Sheets

FIG. 2

FIG. 3

FIG. 4

FIG. 5

FIG. 6
